Primary Examiner — Antoine D Davis(74) *Attorney, Agent, or Firm* — Sutherland Asbill & Brennan LLP(57) **CLAIM**

The ornamental design for a thermostat console, as shown and described.

DESCRIPTION

FIG. 1 is a perspective view of a thermostat console showing my new design;

FIG. 2 is a left side view thereof;

FIG. 3 is a right side view thereof;

FIG. 4 is a front view thereof;

FIG. 5 is a top view thereof;

FIG. 6 is bottom view thereof; and,

FIG. 7 is rear view thereof.

The dotted line showings in FIGS. 1, 2, 3, 5, 6, and 7 form no part of the claimed design.
